RECLOSING CARTON

Reynolds Guyer, St. Paul, Minn., assignor to
 Waldorf Paper Products Company, St. Paul,
 Minn., a corporation of Minnesota

Application September 2, 1937, Serial No. 162,153

9 Claims. (Cl. 229—17)

My invention relates to reclosing cartons and has for an object to provide a carton particularly adapted for use in dispensing powdered, flaky or granular substances, such as may be poured from the carton.

An object of the invention resides in providing a carton which may be easily opened when desired for use, and which may be easily reclosed after the contents thereof have been removed.

10 Another object of the invention resides in providing a carton in which the contents are kept dry and in proper condition and from which the contents will not readily leak out, either prior to or after initial opening of the carton.

15 Another object of the invention resides in providing a carton having a moisture resistant bag within the interior thereof for containing the substance to be dispensed and in constructing said bag and carton so that access to the interior 20 of the bag is had upon opening of the carton.

A still further object of the invention resides in providing a carton in which the upper end is formed through a number of end wall sections issuing from the lateral walls of the carton, which 25 end wall sections are adapted to be simultaneously folded together with the upper marginal portion of the bag to close both the carton and bag.

An object of the invention resides in forming one of the end wall sections with a flap having a 30 tab adapted to be removably secured to one of the other end wall sections, which tab, upon disengagement from the side wall section to which it is attached opens the upper end of the container and in further constructing the other end 35 wall sections to form an opening adapted to be covered by the flap.

A still further object of the invention resides in constructing one of the end wall sections with a slit said tab serving as a tongue for an insertion 40 into the slit to hold the flap in reclosing position.

45 A feature of the invention resides in constructing the folded portions of the bag so that the same form an opening registering with the opening in the carton proper through which the contents of the container may be poured.

Another object of the invention resides in constructing the bag from a glue repellent material which is adapted to maintain certain of the portions of the end wall sections from attachment to one another to facilitate the opening of the cover flap when access to the interior of the carton is desired.

Another object of the invention resides in providing a carton from which the contents may be

readily poured in the removal of the same from the carton.

Other objects of the invention reside in the novel combination and arrangement of parts and in the details of construction hereinafter illustrated and/or described.

In the drawings:

Fig. 1 is a perspective view of a closed carton illustrating an embodiment of my invention.

Fig. 2 is a developed view of the blank from 10 which the carton shown in Fig. 1 is constructed.

Fig. 3 is a fragmentary perspective view of the carton with the parts arranged for filling.

Fig. 4 is a fragmentary perspective view of the carton after filling and showing two of the end 15 wall sections in closing positions.

Fig. 5 is a view similar to Fig. 4 showing another end wall section in position.

Fig. 6 is a perspective view of the carton after the same has been opened in illustrating the manner in which the contents are poured therefrom.

Fig. 7 is a perspective view of the carton after the same has been reclosed.

Fig. 8 is a sectional detail view taken on line 8—8 of Fig. 1 and drawn to a larger scale.

Fig. 9 is a detail sectional view taken on line 9—9 of Fig. 7 and drawn to a larger scale.

My invention comprises a carton or container 10 which is constructed of cardboard or some other suitable material and a paper bag 11 disposed within the same. These parts and their particular association will now be described in detail.

The carton 10 is constructed from a blank 12 of cardboard or some other similar material best 35 shown in Fig. 2. This blank is formed with two longitudinal scores 13 and 14 which extend throughout the length of the blank. The blank is further formed with a number of transverse scores 15, 16, 17 and 18 which form in the blank 40 a front wall 21, a rear wall 22 and two side walls 23 and 24 which constitute the lateral walls of the carton. The marginal portions of the blank 12, outwardly of the scores 13 and 14, are slit along lines 25 and 26 which divide the portions 45 of the carton outwardly of said scores into upper end wall sections 27, 28, 29 and 30 and lower end wall sections 31, 32, 33 and 34. In addition a flap 35 is formed on the front wall 21 which is attached to the side wall 24 forming a tubular 50 structure adapted to be collapsed or extended.

The end wall section 29 is weakened along two diagonal lines 36 and 37 which extend from the intersections of the scores 13, 17 and 18 and converge toward one another. These lines are 55

formed by shearing the blank 12 at the locality indicated at 38 and perforating the blank along the locality indicated at 39. The lines of weakening 36 and 37 are intersected by other lines of 5 weakening 41 which extend parallel to the scores 17 and 18 and terminate at the outer marginal edge 42 of the end section 29. By means of this construction a flap 43 is formed which serves as a cover flap for the opening formed in the upper 10 end of the carton and which will be presently described in detail. This construction further provides a tongue or tab 44 which issues outwardly from the flap 43. It will readily become apparent by tearing the tongue 44 along the lines of 15 weakening 41 and the flap 43 along the lines of weakening 39 that the flap 43 may be completely freed from the end wall section 29 from which the same was formed.

In the end wall section 27 is formed a notch 20 45. In the end wall sections 28 and 30 are similarly formed notches 46 and 47. These notches are so arranged that, when the wall sections are folded into overlying positions, the said notches register with one another and form an opening 25 in the carton, indicated in Fig. 5 by the reference numeral 48.

The bag 11 is constructed from a water resistant or waterproof paper or any other similar suitable material which is also repellent to glue 30 and which is readily flexible. This bag is constructed with a bottom not shown and with a wall structure 49 the upper marginal part of which is designated by the reference numeral 51. The bag 11 is of such dimensions as to be snugly 35 received within the carton 10. The length of the bag 11 is such that the upper marginal part 51 extends upwardly above the score 13 but is of a height above said scores such that its upper edge 52 falls short of the edge of the carton when the 40 parts are folded together.

The method of filling and closing the carton is as follows. As previously stated the blank 12 comes in collapsed tubular form with the flap 35 secured to the side wall 12. The folded structure 45 is first erected into tubular form and the bottom closure formed on the carton by folding the lower end wall sections 31, 32, 33 and 34 upon one another and gluing the same together. This is all accomplished in the usual manner. Thereafter 50 the bag 11 is inserted into the carton and the invention takes the appearance shown in Fig. 3 with the marginal part of the bag extending upwardly above the lateral walls of the carton and along the upper end wall sections 27, 28, 29 and 55 30 which lie in continuation of the lateral walls. The two end wall sections 28 and 30, together with the portions of the marginal part 51 of the bag 11 adjacent the said end wall sections are folded inwardly into closing position. This forms doubled over flaps 53 and 54 on the bag which have 60 diagonally folded edges 55. The end sections 27 and 29, together with the flaps 53 and 54, are then folded outwardly. The arrangement of parts, after this operation is completed, is shown 65 in Fig. 4. While the parts are so held two glue collars are run over the inner surfaces of the flaps 53 and 54 and the end wall sections 27 and 29. The bag 11 as stated is constructed of a suitable glue repellent material such as parchment or wax paper. This prevents the glue from 70 adhering to the same and coating only the corner portions 56 and 57 of the end wall sections 27 and 29, extending outwardly beyond the flaps 53 and 54. The lines of weakening 36 and 37 are so 75 arranged that they substantially coincide with

the edges 55 of flaps 53 and 54. In this manner glue is applied only to the corner portions 56 and 57 and to the tab or tongue 44. It will be noted that the height of the marginal part 51 of bag 11 is such that the major portion of the cover flap 43 is covered and no glue is applied thereto. Also the size of the notch 45 is such that glue is applied only to the corner portions 57 of the end section 27. After the glue has been applied, end section 27, together with the flap 54, are folded 10 inwardly and the corner portions 57 cause to adhere to the outermost surfaces of the end wall sections 28 and 30. The arrangement of parts after section 27 has been folded is shown in Fig. 5. End wall section 29 together with flap 53, is next 15 folded upon the end wall section 27 and caused to adhere thereto through the adhesive applied to the corner portions 56 of said end wall section. The parts then become arranged as shown in Fig. 1. The carton is now completely closed 20 and ready for use. Due to the fact that the marginal portion of the bag is formed into doubled over flaps on account of the manner in which the parts are folded together, a tight closure is formed at the end of the carton which prevents 25 leakage of the contents thereof through the end closure.

Along an area adjacent the score 13 and on the outer surface of end wall section 27 is provided printing indicated at 58 which is of a width 30 less than the width of the tongue or tab 44. This printing is of such nature that it prevents sticking of the glue to the same, thereby leaving the extreme end of the tab 44 unattached to the carton. The tongue hence becomes attached to 35 the carton only along a narrow band designated by the reference numeral 59 in Fig. 5. When it becomes desired to open the carton, the tab 44 is grasped and pulled loose from the end wall section 27. At the same time the lines of weakening formed by the perforations 41 causes the tab 44 to become separated from the remaining portion of the end wall section 29. The flap 43 next becomes disengaged from the end wall section 29 due to the shear lines 38, and upon further pulling of the tab 44 away from the end wall section 29 said tab is broken along the lines of perforation 39 until both tongue and flap are free from the end wall section 29 to hinge about the hinge formed through the score 13. When 40 raised to a position in alignment with the rear wall 22, from which the flap 43 issues, the opening 61 in the bag 11 becomes exposed. In the event that the flap 53 is partly adhered to the end wall section 27 the same can readily be disengaged therefrom after flap 43 has been freed 45 so that said flaps may be moved jointly into the position shown in Fig. 6. The contents may now be poured out of the bag 11, the flaps 53 and 43 serving as a spout to assist in directing the contents of the carton to the desired locality.

To facilitate removal of the contents of the carton certain of the walls of the carton are formed so that the same will bend giving the rear wall 22 and flap 43 a U-shaped formation. 50 This is accomplished as follows. In the rear wall 22 is provided two diagonal scores 62 and 63 which extend from the locality of the scores 17 and 18 up to the score 13 at a point in the middle of the flap 43. Connected with this score is another score 64 which extends directly across the flap 43 and tab 44. In the end section 27 are similarly formed diagonally arranged scores 65 and 66 which commence at the intersections of scores 13, 15 and 16 and terminate at the edge 55

of the notch 45. Similar scores 67, 68 and 69 are formed in the end wall sections 28, 30 and 29 which register with the scores 65 and 66. By means of these scores folding of the rear wall 22 and the flap 43 into U-shaped formation is greatly facilitated.

After the carton has once been opened the same may be reclosed in the following manner. The flap 54 is unattached to the end wall section 27 and forms therebetween a pocket 58, Fig. 9. Tab 44 is inserted into this pocket through a slit 71 formed in the end wall section 29. The arrangement of parts, after the container has been so closed, is shown in Figs. 7 and 9.

The advantages of my invention are manifest. An extremely simple and practical reclosing carton is provided which functions positively and effectively in the desired manner. The carton can be constructed by ordinary machinery available for the purpose and likewise the carton can be filled and the ends sealed by machinery now used for the required purpose. The carton can be constructed at no additional expense whatsoever over and above the cost of cartons of the same style and dimensions. The bag within the carton is utilized for preventing adhesion of the end wall sections to one another where not desired so that the various parts operate in the desired manner.

Changes in the specific form of my invention, as herein disclosed, may be made within the scope of what is claimed without departing from the spirit of my invention.

Having described my invention, what I claim as new and desire to protect by Letters Patent is:

1. In combination, a carton constructed from a sheet of material formed to provide lateral walls including a front wall, a rear wall, and side walls, and a bottom connected therewith, end wall sections issuing outwardly from the upper ends of said lateral walls and being adapted to be folded over and secured together to form an end wall for the upper end of the carton, a bag within said carton, the marginal part of the bag at the open end thereof projecting beyond said lateral walls and being foldable with said end wall sections to close the upper end of the bag, the extent of said marginal part of the bag beyond the lateral walls being less than one half the width of the carton to cause the edges of said bag to fall short of one another to leave a discharge opening in the bag when the portions of the marginal part of the bag adjacent the side walls of the carton are folded toward one another one of said end wall sections having a removably attached part serving as a cover for said opening.

2. In combination, a carton constructed from a sheet of material formed to provide lateral walls including a front wall, a rear wall, and side walls, and a bottom connected therewith, end wall sections issuing outwardly from the upper ends of said lateral walls and being adapted to be folded over and secured together to form an end wall for the upper end of the carton, a bag within said carton, the marginal part of the bag at the open end thereof projecting beyond said lateral walls and being foldable with said end wall sections to close the upper end of the bag, the extent of said marginal part of the bag beyond the lateral walls being less than one half the width of the carton to cause the edges of said bag to fall short of one another to leave a discharge opening in the bag when the portions of the marginal part of the bag adjacent the side walls of the carton are folded toward one another, certain

of the end wall sections being constructed to form an opening in the end wall communicating with the opening in the bag, and one of said end wall sections forming a cover for closing said opening in the end wall.

3. In combination, a carton constructed from a sheet of material formed to provide lateral walls including a front wall, a rear wall, and side walls, and a bottom connected therewith, end wall sections issuing outwardly from the upper ends of said lateral walls and being adapted to be folded over and secured together to form an end wall for the upper end of the carton, a bag within said carton, the marginal part of the bag at the open end thereof projecting beyond said lateral walls and being foldable with said end wall sections to form folded flaps on the bag, the extent of said marginal part of the bag beyond the lateral walls being less than one half the width of the carton to cause the edges of the bag to fall short of one another to leave a discharge opening in the bag when the end wall sections issuing from the side walls of the carton and the adjacent portion of the bag are folded toward one another, said flaps being adapted to cover said opening in the bag when folded with the end wall sections issuing from the front wall and rear wall, the end wall section issuing from the front and side walls being constructed with registering notches adapted to form an opening in the end wall communicating with said opening in the bag and the end wall section issuing from the rear wall forming a cover for the opening in the end wall.

4. In combination, a carton constructed from a sheet of material formed to provide lateral walls including a front wall, a rear wall, and side walls, and a bottom connected therewith, end wall sections issuing outwardly from the upper ends of said lateral walls and being adapted to be folded over and secured together to form an end wall for the upper end of the carton, a bag within said carton, the marginal part of the bag at the open end thereof projecting beyond said lateral walls and being foldable with said end wall sections to form triangular shaped folded flaps on the bag, the extent of said marginal part of the bag beyond the lateral walls being less than one half the width of the carton to cause the edges of the bag to fall short of one another to leave a discharge opening in the bag when the end wall sections issuing from the side walls of the carton and the adjacent portion of the bag are folded toward one another, said flaps being adapted to cover said opening in the bag when folded with the end wall sections issuing from the front wall and rear wall, the end wall sections issuing from the side walls and said front wall being constructed to form an opening in the end wall communicating with the opening in the bag, a triangular shaped flap struck out of the end wall section issuing from the rear wall and overlying said triangular flap on the bag.

5. In combination, a carton constructed from a sheet of material formed to provide lateral walls including a front wall, a rear wall, and side walls, and a bottom connected therewith, end wall sections issuing outwardly from the upper ends of said lateral walls and being adapted to be folded over and secured together to form an end wall for the upper end of the carton, a bag within said carton, the marginal part of the bag at the open end thereof projecting beyond said lateral walls and being foldable with said end wall sections to form triangular shaped folded flaps on the bag, the extent of said marginal part of the bag be-

yond the lateral walls being less than one half the width of the carton to cause the edges of the bag to fall short of one another to leave a discharge opening in the bag when the end wall sections, issuing from the side walls of the carton and the adjacent portion of the bag are folded toward one another said flaps being adapted to cover said opening in the bag when folded with the end wall sections issuing from the front wall 10 and rear wall, the end wall sections issuing from the side walls and said front wall being constructed to form an opening in the end wall communicating with the opening in the bag, a triangular shaped flap struck out of the end wall section issuing from the rear wall and overlying said triangular flap on the bag, said end wall flap and said bag flap conforming in configuration, and being of substantially the same dimensions.

6. In combination, a carton constructed from a sheet of material formed to provide lateral walls including a front wall, a rear wall, and side walls, and a bottom connected therewith, end wall sections issuing outwardly from the upper ends of said lateral walls and being adapted to be folded over and secured together to form an end wall for the upper end of the carton, a bag within said carton, the marginal part of the bag at the open end thereof projecting beyond said lateral walls and being foldable with said end wall sections to form triangular shaped folded flaps on the bag, the extent of said marginal part of the bag beyond the lateral walls being less than one half the width of the carton to cause the edges of the bag to fall short of one another to leave an opening in the bag when the end wall sections, issuing from the side walls of the carton and the adjacent portion of the bag are folded toward one another, said flaps being adapted to cover said opening in the bag when folded with the end wall sections issuing from the front wall and rear wall, the end wall sections issuing from said side walls and said front wall being constructed to form an opening in the end wall communicating with the opening in the bag, a triangular shaped flap struck out of the end wall section issuing from the rear wall and overlying said triangular flap on the bag, said end wall flap and said bag flap conforming in configuration and being of substantially the same dimensions, said end wall sections issuing from the front and rear wall and said bag flaps being adapted to be bent outwardly at right angles to the front and rear walls to facilitate the simultaneous application of adhesive to said end wall sections and the overlying bag flaps, one of said bag flaps serving as a mask for preventing application of adhesive to said end wall flap to accommodate ready detachment thereof from the end wall, said end wall flap having a tab on the end of the same, said overlying bag flap falling short of said tab to provide an adhesive coated area on the tab for adhering said tab to the opposite end wall section.

7. In combination, a carton constructed from a sheet of material formed to provide lateral walls including a front wall, a rear wall, and side walls, and a bottom connected therewith, end wall sections issuing outwardly from the upper ends of said lateral walls and being adapted to be folded over and secured together to form an end wall for the upper end of the carton, a bag within said carton, the marginal part of the bag at the open end thereof projecting beyond said lateral walls and being foldable with said end wall sections to form triangular shaped folded flaps on the bag, the extent of said marginal part of the bag beyond the lateral walls being less than one half the width of the carton to cause the edges of the bag to fall short of one another to leave an opening in the bag when the end wall sections, issuing from the side walls of the carton and the adjacent portion of the bag are folded toward one another, said flaps being adapted to cover said opening in the bag when folded with the end wall sections issuing from the front wall and rear wall, the end wall sections issuing from said side walls and said front wall being constructed to form an opening in the end wall communicating with the opening in the bag, a triangular shaped flap struck out of the end wall section issuing from the rear wall and overlying said triangular flap on the bag, said end wall flap and said bag flap conforming in configuration, and being of substantially the same dimensions, said end wall sections issuing from the front and rear wall and said bag flaps being adapted to be bent outwardly at right angles to the front and rear walls to facilitate the simultaneous application of adhesive to said end wall sections and the overlying bag flaps, one of said bag flaps serving as a mask for preventing application of adhesive to said end wall flap to accommodate ready detachment thereof from the end wall, and means for detachably securing said end wall flap to the end wall.

8. In combination, a carton constructed from a sheet of material formed to provide lateral walls including a front wall, a rear wall, and side walls, and a bottom connected therewith, end wall sections issuing outwardly from the upper ends of said lateral walls and being adapted to be folded over and secured together to form an end wall for the upper end of the carton, a bag within said carton, the marginal part of the bag at the open end thereof projecting beyond said lateral walls and being foldable with said end wall sections to form triangular shaped folded flaps on the bag, the extent of said marginal part of the bag beyond the lateral walls being less than one half the width of the carton to cause the edges of the bag adjacent the side walls of the bag to fall short of one another to leave an opening in the bag when the end wall sections, issuing from the side walls of the carton and the adjacent portion of the bag are folded toward one another, said flaps being adapted to cover said opening in the bag when folded with the end wall sections issuing from the front wall and rear wall, the end wall sections issuing from said side walls and said front wall being constructed to form an opening in the end wall communicating with the opening in the bag, a triangular shaped flap struck out of the end wall section issuing from the rear wall and overlying said triangular flap on the bag, said end wall flap and said bag flap conforming in configuration, and being of substantially the same dimensions, said end wall sections issuing from the front and rear wall and said bag flaps being adapted to be bent outwardly at right angles to the front and rear walls to facilitate the simultaneous application of adhesive to said end wall sections and the overlying bag flaps, one of said bag flaps serving as a mask for preventing application of adhesive to said end wall flap to accommodate ready detachment thereof from the end wall, and the other bag flap serving as a mask for preventing application of adhesive to a portion of the corresponding end section to form a pocket therebetween said end wall section having a slit therein and a tongue on said end wall flap insertable through said slit and into said pocket.

9. In combination, a carton constructed from a sheet of material formed to provide lateral walls including a front wall, a rear wall, and side walls, and a bottom connected therewith, end wall sections issuing outwardly from the upper ends of said lateral walls and being adapted to be folded over and secured together to form an end wall for the upper end of the carton, a bag within said carton, the marginal part of the bag at the open end thereof projecting beyond said lateral walls and being foldable with said end wall sections to form triangular shaped folded flaps on the bag, the extent of said marginal part of the bag beyond the lateral walls being less than one half the width of the carton to cause the edges of the bag to fall short of one another to leave an opening in the bag when the end wall sections, issuing from the side walls of the carton and the adjacent portion of the bag are folded toward one another, said flaps being adapted to cover said opening in the bag when folded with the end wall sections issuing from the front wall and rear wall, the end wall sections issuing from said side walls and said front wall being constructed to form an opening in the end wall communicating with the opening in the bag, a triangular shaped flap struck out of the end wall section issuing from the rear wall and overlying said triangular flap on the bag, said end wall flap and said bag flap conforming in configuration, and being of substantially the same dimensions, said end wall sections issuing from the front and rear wall and said bag flaps being adapted to be bent outwardly at right angles to the front and rear walls to facilitate the simultaneous application of adhesive to said end wall sections and the overlying bag flaps, one of said bag flaps serving as a mask for preventing application of adhesive to said end wall flap to accommodate ready detachment thereof from the end wall, and the other bag flap serving as a mask for preventing application of adhesive to a portion of the corresponding end section to form a pocket therebetween said end wall section having a slit therein and a tongue on said end wall flap insertable through said slit and into said pocket.

9. In combination, a carton constructed from a sheet of material formed to provide lateral walls including a front wall, a rear wall, and side walls, and a bottom connected therewith, end wall sections issuing outwardly from the upper ends of said lateral walls and being adapted to be folded over and secured together to form an end wall for the upper end of the carton, a bag within said carton, the marginal part of the bag at the open end thereof projecting beyond said lateral walls and being foldable with said end wall sections to form triangular shaped folded flaps on the bag, the extent of said marginal part of the bag beyond the lateral walls being less than one half the width of the carton to cause the edges of the bag adjacent the side walls of the bag to fall short of one another to leave an opening in the bag when the end wall sections issuing from the side walls of the carton and the adjacent portion of the bag are folded toward one another, said flaps being adapted to cover said opening in the bag when folded with the end wall sections issuing from the front wall and rear wall, the end wall sections issuing from said side walls and said front wall being constructed to form an opening in the end wall communicating with the opening in the bag, a triangular shaped flap struck out of the end wall section issuing from the rear wall and overlying said triangular flap on the bag, said end wall flap and said bag flap conforming in configuration and being of substantially the same dimensions, 10 said end wall sections issuing from the front and rear wall and said bag flaps being adapted to be bent outwardly at right angles to the front and rear walls to facilitate the simultaneous application of adhesive to said end wall sections and 15 the overlying bag flaps, said bag flaps serving as masks for preventing application of adhesive to certain areas of the juxtaposed end wall sections, said bag being constructed from an adhesive repellent material. 20

REYNOLDS GUYER.
